UNITED STATES PATENT OFFICE.

LAURI W. LARSON, OF CANTERBURY, CONNECTICUT.

LETTER-BOX.

1,299,740.

Specification of Letters Patent. Patented Apr. 8, 1919.

Application filed March 22, 1917. Serial No. 156,709.

To all whom it may concern:

Be it known that I, LAURI W. LARSON, a citizen of the United States, residing at Canterbury, in the county of Windham and State of Connecticut, have invented certain new and useful Improvements in Letter-Boxes, of which the following is a specification.

This invention has relation to certain new and useful improvements in letter boxes and has for its primary object, the provision of a letter box of improved and simplified construction, and in which will be provided a draw which may be readily withdrawn from one end of the box for the purpose of depositing or removing mail matter and which carries a signal operating member which will serve to operate a signal to one position as the draw is closed and operate the signal in the reverse direction as the draw is opened or withdrawn.

The invention has for another object, the provision of improved and novel draw operating means which will be below the box and out of the way.

The invention has for a further object, the provision of a letter box of the above stated character which will be of such construction as to be completely water-tight when closed.

With these above and other objects in view the invention resides in the novel construction, combination, and arrangement of parts as hereinafter set forth in the specification, pointed out in the claims and shown in the accompanying drawings, in which:—

Figure 1 is a longitudinal section through the complete device with the draw shown in open position by dotted lines.

Fig. 2 is a side elevation with the draw in open position and the signal indicated in upright position by dotted lines;

Fig. 3 is a transverse vertical section on the plane of line 3—3 of Fig. 1 looking in the direction indicated by the arrows.

Referring more particularly to the drawings in which similar reference characters designate corresponding parts throughout the several views, 1 designates the body of the box which is preferably of elongated form and has one end closed, while its opposite end is open and is adapted to be closed by the outer end or head 2 of the sliding draw 3, said head 2 having a continuous

flange 4 formed on its inner face for engagement with the inner face of the body 1 around the open end thereof for the purpose of preventing water from entering said body 1.

The main portion of the draw 3 consists of a horizontal plate forming a draw bottom and having its opposite longitudinal edges engaged in the U-shaped guides 5 secured to the inner face of the body 1 adjacent the bottom thereof and entering the sides of the same, the front end of the plate being secured to the inner face of the head 2, as shown at 6 while the rear end or inner end 7 is extended upwardly for a suitable distance to prevent the mail matter from sliding off this end of the plate as the draw is withdrawn or moved outwardly. Secured to the outer face of the head 2, as shown at 8, is the angular end of a trigger arm 9 which is extended for sliding movement against the outer face of one side of the body 1 as the draw is moved inwardly and outwardly, said trigger arm 9 having a lip 10 formed on its free rear end for engagement with the weighted right angled lower end 11 of the signal arm 12 which is pivoted at its lower end, as shown at 13 to one side of the body 1, said signaling arm 12 having a suitable signal 14, preferably in the form of a flag, as shown in Fig. 2 formed upon its upper end. The signaling arm 12 is also of such length that the signal 14 may project slightly above the body 1 as shown by dotted lines in Fig. 2 and by full lines in Fig. 3 when the signaling arm 12 is in upright position.

When the draw is forced inwardly or closed after the deposit of mail matter upon the same, the lip 10 of the trigger arm 9 engages the weighted rightangled lower end 11 of the signaling arm 12 and swings the same to the position shown by dotted lines in Fig. 2, thereby moving the signaling arm 12 to upright position so that the signal 14 may appear above the body 1 to give notice that mail matter has been deposited in the letter box. It will be understood that when the draw is in closed position the lip 10 is engaged behind arm 12 and engages the free extremity of the same, whereby upon outward movement of the draw, the lip 10 will serve to release the signal by moving away from the weighted rightangled lower end 11.

of the signaling arm 12 and permitting the signal to again drop to the position shown by full lines in Fig. 2.

The draw has a depending bracket 15 secured to the end face of the draw 3 forming the bottom of the draw and this bracket 15 extends slightly through an elongated longitudinal slot 16 formed in the bottom of the body 1. Pivoted to the lower end of the bracket 15, as shown at 17, is a slotted operating arm 18, within the elongated slot 19 of which are engaged the guide rollers 20 projecting from one side of the draw opening and closing lever 21 which has an enlarged operating lower free end 22 and which is pivoted intermediate its end, as shown at 23, to the depending central portion of the supporting rod 24 which has its opposite ends extended upwardly and secured in a suitable manner to the bottom of the body 1, adjacent the opposite ends of the latter.

From the foregoing it will be readily seen that I have provided an improved and novel form of draw opening and closing means, as well as the improved form of draw for a letter box and when the draw is closed it will automatically lock as the signal swings to upright position and can not again be opened until the signal is turned slightly to release the lip 10 from the weighted right-angled lower end 11 of the signaling arm 12.

While the preferred embodiments of the invention has been clearly shown, it will be understood that minor changes in the details of construction and arrangement of parts may be resorted to within the scope of the appended claims without departing from the spirit of the invention or sacrificing any of the advantages of the same.

40 What is claimed is:

1. A letter box comprising a body having a slotted portion, a draw slideable through one end of said body, means carried by one

end of said draw to securely close said end of the body, a draw lever, connections between said lever and said draw, said connections extending through said slotted portion, a signal pivoted to said body, and a trigger arm carried by said draw for engagement with said signal to operate the same and lock the draw against outward movement.

2. A letter box including a body, a draw slidably mounted therein, a slotted arm pivotally secured to said draw and extending through said body, a lever pivotally supported by said body and a connection between one end of said lever and said slotted arm.

3. A letter box including a casing open at one end and provided with a longitudinal slot, a draw slidably mounted in said casing and equipped with a closure for the open end thereof, a slotted arm pivotally secured to said draw and movable in the slot in said casing, a lever pivotally supported by said casing, and rollers carried by one end of said lever and engaged in the slot in said arm.

4. A letter box including a casing, a draw slidably mounted therein, a signal arm pivoted to said casing, an angular extension formed on the lower end of said arm, a trigger arm carried by said draw and adapted at times to be extended beneath said extension to support the signal arm in a vertical position, and a locking lip carried by the extremity of said trigger arm and adapted to be engaged beyond the extremity of said angular extension to prevent accidental or casual opening of the draw.

In testimony whereof I affix my signature 80 in presence of two witnesses.

LAURI W. LARSON.
